UNITED STATES PATENT OFFICE.

ROY CALHOUN, OF TYLERTOWN, MISSISSIPPI.

REVOLVING SHELF.

1,243,651.

Specification of Letters Patent. Patented Oct. 16, 1917.

Application filed February 4, 1914. Serial No. 816,401.

To all whom it may concern:

Be it known that I, Roy CALHOUN, a citizen of the United States, residing at Tylertown, in the county of Pike and State 5 of Mississippi, have invented new and useful Improvements in Revolving Shelves, of which the following is a specification.

The invention relates to revolving shelves, and more particularly to the class of display racks or cases.

The primary object of the invention is the provision of a rack or casing wherein the shelves are movable and driven in any suitable manner so that the articles supported on the said shelves can be brought in convenient reach of a person for the removal thereof from the same.

Another object of the invention is the provision of a display case wherein any particular shelf can be stopped in its travel at the desired point for free accessibility thereto, the stop mechanism being of a novel form so that the revolving shelves will be stopped to position any particular shelf thereof in a position to permit the convenient removal of an article or articles therefrom.

A still further object of the invention is the provision of a case of this character which is practical in construction, attractive in appearance, and in which the articles or goods supported on the shelves thereof can be continuously displayed, and also by the particular arrangement a greater economy 35 of space is obtained, as well as convenient access to the articles or goods supported by the shelves within the case.

A still further object of the invention is the provision of a show case wherein the shelf structure is of novel form, possessing simplicity of construction, assuring efficiency in operation, and also which is inexpensive in manufacture.

With these and other objects in view, the invention consists in the construction, combination and arrangement of parts as will be hereinafter fully described, illustrated in the accompanying drawing, and pointed out in the claim hereunto appended.

50 In the drawings:—

Figure 1 is a front elevation of a show case constructed in accordance with the invention.

Fig. 2 is a vertical transverse sectional view thereof.

Fig. 3 is a horizontal sectional view on the line 3—3 of Fig. 2.

Fig. 4 is a perspective view of the adjustable stop mechanism.

Fig. 5 is a perspective view of the adjustable arm of the stop mechanism.

Similar reference characters indicate corresponding parts throughout the several views in the drawings.

Referring to the drawings in detail, A 65 designates a suitable case or housing of any desirable shape, and is preferably provided with a transparent glass front including a drop door B adapted to be supported in horizontal position by means of the sliding braces C of any ordinary well-known construction, so that the door can serve as a rest for the articles removed from the case. On the opening of the door B access is readily had to the interior of the 70 case for removing goods or articles from the revolving shelf mechanism presently described.

Mounted in the lower portion or on the bottom of the case A is an electric motor 10, 80 the drive shaft 11 of which has worm gear connection with a further shaft 13 journaled in bearings 14 suitably mounted on opposite sides of the case A, the shaft 13 being horizontally disposed a distance above 85 the motor, and carries spaced sprocket wheels 15 over which are trained the sprocket chains 16 for supporting the shelves presently described.

The sprocket chains 16 are of the endless 90 type, and are also trained over sprocket wheels 17 fixed to stud spindles 18 arranged near the top of the case and disposed horizontally in bearings 19 fixed to the sides 95 of the said casing, so that on rotating the shaft 13 motion will be imparted to the various carriers or shelves supported by the sprocket chains 16, the said carriers or shelves being hereinafter more fully described.

The carriers or shelves are of a similar construction, and each comprises a base section 20 and ends 21 formed with stud sleeves 22 projecting outwardly therefrom for suspending the carriers or shelves between the 105 chains 16 from studs 23 which are passed through the sleeves 22 and are mounted in the links of the chain 16 at predetermined intervals thereof. These carriers or shelves will at all times assume a position to hold 110

articles or goods as they are suspended and will gravitate to such position during the travel of the chain so that the bases 20 will be sustained horizontal. The carriers are 5 adapted for the reception of articles or goods of any character, and during the travel of the chain 16 the said carriers will be brought to the front of the case for displaying their contents advantageously.

10 Mounted in the inner face of one side of the case is a cut-off switch which is arranged in the circuit of the electric motor 10 for the opening or closing thereof by swinging the arm 24 of the said switch, and in this manner the motor 10 can be started or stopped at will. Suitably journaled in the sides of the case A is a horizontally disposed rocking shaft or bar 25, the major portion of which is of rectangular shape in cross section to form flat faces 26, the shaft or bar 25 being disposed contiguous to the doorway in the front of the case A for free accessibility, and on the outermost flat face thereof is arranged suitable indicia 27 such 20 as letters or numerals, while slidably embracing the rectangular-shaped portion of the shaft or bar 25 is a rectangular collar or sleeve portion 28 of a striking finger or arm 29, the latter being projected rearwardly for engagement with any one of a series of projections 30 arranged singly on the respective bases 20 of the shelves to protrude beyond the front edge thereof, the projections 30 being arranged in staggered relation to 30 each other to align with the indicia 29 on the bar or shaft 25. That is to say, each projection 30 aligns with one of the characters 27 on the bar or shaft 25 so that the particular character will designate one of the shelves or carriers, thus enabling the collar or sleeve 28 to be adjusted on the shaft or bar 25 in a position whereby the arm or finger 29 will be disposed in the path of the projection 30 for contact therewith, and thus 40 rock the shaft or rod 25 which has fixed thereto near one end a trip lever 31, the tripping nib 32 of which is projected into the path of the arm 24 of the switch so that the latter will be automatically thrown to cut off position on the rocking of the shaft for the stopping of the motor, thereby bringing the desired carrier to a standstill directly in front of the door B so that access may be had thereto for the removal of its contents.

45 The collar or sleeve 28 at the front thereof is formed with a peep opening 33, which enables the reading of the characters 27 on the

bar or shaft 25 on the shifting of the collar or sleeve 28 directly over any of the characters, the collar having formed upon one 60 side thereof a hand hold 34 arranged between the arm 29 and peep opening 33. Said handle enables the convenient sliding of the collar to adjusted position.

Connected to the trip lever 31 at its free 65 end is one end of a coiled retractile spring 35 which has its opposite end connected to the side of the case A and is adapted to exert a pull upon the trip lever 31 to normally hold it against a stop 36 fixed to the 70 side of the casing A, and thereby hold the rod or bar 25 against rocking movement so that the finger or arm 29 will be projected to engage one of the series of projections 30 on the shelves. It is to be understood, however, that normally the arm or finger 29 is positioned at any point between the path of movement of the projections 30 so as not to interfere with the rotation of the carriers when the motor 10 is operated, so that the 80 articles or goods in the carriers will be brought to view by the successive travel of the carriers to the front of the case.

75 On the arm 24 of the switch is a handle 37 which enables the manual manipulation 85 of the arm for the opening and closing of the circuit, thereby enabling the motor to be stopped or started at will.

From the foregoing it is thought that the construction and manner of operation of 90 the device will be clearly understood, and therefore a more extended explanation has been omitted.

What is claimed is:—

In a device of the class described, a casing 95 having an opening extending transversely of the front thereof, a stop member on said casing adjacent an end of said opening, movable supports within said casing, means 100 for moving said supports, controlling mechanism for said means including a rock shaft within said casing contiguous to said opening and operable by said movable supports, a switch in said casing above said stop member, and a trip arm on said rock shaft to 105 engage said switch normally held in contact with said stop member.

In testimony whereof I affix my signature in presence of two witnesses.

ROY CALHOUN.
